(57) **CLAIM**

The ornamental design for a latch backing plate, as shown and described.

DESCRIPTION

FIG. 1 is a first perspective view of a first embodiment of a latch backing plate;

FIG. 2 is a top view of the latch backing plate of FIG. 1; FIG. 3 is a front side view of the latch backing plate of FIG. 1;

FIG. 4 is a rear side view of the latch backing plate of FIG. 1;

FIG. 5 is a bottom view of the latch backing plate of FIG. 1;

FIG. 6 is a first side view of the latch backing plate of FIG. 1;

FIG. 7 is a second side view of the latch backing plate of FIG. 1;

FIG. 8 is a second perspective view of the latch backing plate of FIG. 1;

FIG. 9 is a first perspective view of a second embodiment of a latch backing plate;

FIG. 10 is a top view of the latch backing plate of FIG. 9; FIG. 11 is a front side view of the latch backing plate of FIG. 9;

FIG. 12 is a rear side view of the latch backing plate of FIG. 9;

FIG. 13 is a bottom view of the latch backing plate of FIG. 9;

FIG. 14 is a first side view of the latch backing plate of FIG. 9;

FIG. 15 is a second side view of the latch backing plate of FIG. 9; and,

FIG. 16 is a second perspective view of the latch backing plate of FIG. 9.

The broken lines in the figures show portions of the latch backing plate that form no part of the claimed design.

1 Claim, 12 Drawing Sheets
